UNITED STATES PATENT OFFICE

CARL V. POHLSON, OF PAWTUCKET, RHODE ISLAND

DESIGN FOR A COMBINED BRUSH AND HAT HOLDER

Application filed March 31, 1930. Serial No. 35,072. Term of patent 7 years.

To all whom it may concern:

Be it known that I, CARL V. POHLSON, a citizen of the United States of America, residing in Pawtucket, county of Providence, State of Rhode Island, have invented a new, original, and ornamental Design for a Combined Brush and Hat Holder, of which the following is a specification, reference being had to the accompanying drawing, forming a part thereof.

The figure is a perspective view of a combined brush and hat holder, showing my new design.

I claim:

The ornamental design for a combined brush and hat holder, substantially as shown.

CARL V. POHLSON.
